UNITED STATES PATENT OFFICE

2,121,505

BOOKBINDING

Harvey B. Martling, Nashville, Tenn.

Application April 15, 1937, Serial No. 137,137

9 Claims. (Cl. 281—21)

This invention relates to book binding and more particularly to books bound in such manner as to permit the leaves or pages to be opened out flat or substantially flat without appreciable inherent tendency to close upon themselves. Certain features of the invention relate to improvements in the book binding disclosed and claimed in my United States Patent 2,014,973, of September 17, 1935. Other features of the present invention are applicable more generally to various other types of book bindings.

An object of the invention is to provide a book or book binding in which the pages may be opened out flat or substantially flat with no appreciable tendency to close upon themselves, and in which the leaves or pages are firmly secured to the book back and covers.

Another object is to provide a book or book binding in which the leaves or pages are secured to other parts by means of a double anchorage.

A further object is to provide a book or book binding in which the leaves or pages are anchored to the covers independently of their connection to the book back.

Other objects will become apparent from a reading of the following description, the appended claims and the accompanying drawing, in which:

Figure 1 is a perspective view of a book embodying the invention;

Figure 2 is a transverse sectional view showing a book embodying the invention with the covers only in opened position and with certain parts shown as of exaggerated thickness;

Figure 3 is a transverse sectional view of a book embodying the invention and in open position; and,

Figure 4 is a detail perspective view of a back-binding member.

The illustrated embodiment of the invention shown in the drawing includes a back generally designated A, covers B—B operatively connected or hinged to the back as at 1—1, a stack of leaves C provided with spaced sets of registering openings 2 adjacent the inner edges of the leaves and bound to the back and cover by means to be described.

The back A includes a back proper comprising an outside sheet 3 of fabric or other suitable finishing material which is extended beyond the back and on to the face of the covers B—B, and a stiffening strip 4, preferably of fiber or other suitable material, which is glued to the inside of the sheet 3, as shown clearly in Figure 2. The

back A and covers B—B constitute the book's outer structure.

For securing or anchoring the leaves to the back proper, there is provided a plurality of flexible retaining or attaching bands 5 threaded through the openings 2 in the sheets and anchored to the back A. In accordance with the invention, there is provided an improved back-binding member D for effecting this anchorage, the member D being shown clearly in Figures 2 and 4. As shown, this improvement comprises a sheet of flexible material, preferably light fiber board or the like, which is twice-folded lengthwise of the back A with the two folds extending respectively adjacent the opposite edges of the back proper. As thus folded, the member is of collapsed Z formation (the Z being shown reversed in Figures 2 and 4). The folding of the sheet to form the member D divides it into sections D¹, D², and D³. The right hand edge of the section D¹, as viewed in Figure 4, is glued to the adjacent edge portion of the section D², so that the sections D¹ and D² are joined adjacent their edges but are free from jointure intermediate their edges. As thus joined, the sections D¹ and D² therefore constitute a flattened tube, and the section D³ constitutes a projecting wing appended to the tube.

The back-binding member is formed with openings D⁴ spaced along the fold between the sections D² and D³ so as to register with the respective sets of openings 2 in the leaves.

The flexible attaching bands 5 preferably are embedded in the back A and in the form shown are threaded through the openings 2 in the leaves and the openings D⁴ in the back-binding member, as shown most clearly in Figure 2. One end portion of each band 5 extends through an opening D⁴ in the back-binding member and is glued between the adjacent edge portions of the sections D² and D³ of the back-binding member and the opposite end portion of each attaching band extends between and is glued between the other edge portions of the sections D² and D³. The section D³ is firmly glued over its entire outside surface to the stiffening strip 4, thereby anchoring the entire back-binding member D and with it the bands 5 and the leaves to the back proper.

Since the flattened tube constituted by the sections D¹ and D² of the back-binding member D is free from jointure intermediate its edges, the sections D¹ and D² are separable or relatively movable intermediate their edges, whereby flexibility of the binding is increased, with the result

that the book can be opened out very flat without any inherent tendency of the pages or leaves to close upon themselves. However, it should be observed that the section D² is stiffened because 5 of its being joined to the stiffening strip 4, as a result of which the section D¹ of the flattened tube does most of the flexing when the book is opened. This construction, therefore, provides stiffness of the back proper but flexibility of the 10 binding as a whole.

In accordance with a further feature of the invention, there are provided two reinforcing strips E preferably of light fabric material which are connected respectively as by glueing to the inside 15 edge portions of the outside leaves and also to the adjacent inside edge portions of the associated covers. Each of the strips E is folded lengthwise to provide a hinge portion 7, a portion 8 connected to the adjacent outside leaf and a portion 9 connected to the adjacent cover. Each strip portion 8 is formed with a plurality of spaced openings 10 which register with the openings 2 in the leaves and each portion 9 is formed with a plurality of openings 11 which are aligned 20 with the openings 10 and spaced therefrom transversely of the book. The attaching bands 5 extend through the openings 10, thence across the hinge portions 7, thence through the openings 11 in the strip portions 9, and thence to the 25 back-binding member D, to which they are anchored, as previously described.

The passage of the bands 5 through the spaced openings in the reinforcing strips E provides for anchoring the leaves to the book covers B independently of their anchorage to the back A, so that if the back should become damaged, the leaves still would be securely connected to the 30 covers B. It will be observed that the bands 5 provide for dual anchorage of the leaves to the 35 covers and to the back. The arrangement providing the dual anchorage is strong and durable and yet does not interfere with the flexibility and flat opening properties of the book considered as a whole. Preferably, the portions 9 of the reinforcing strips are glued under the trimming or inside facing sheets 12 of the covers as shown at 13. Preferably the extreme inner edges of the leaves are glued to the section D¹ of the member D, as shown at 14 in Figure 2.

60 The book disclosed for the purposes of illustration embodies the invention in a practical and the now preferred form, but it is apparent that the specific construction and relative arrangement of the parts may be modified without departing from the invention as defined in the claims.

I claim:

65 1. In a book, the combination of a back; covers operatively connected to said back; a stack of leaves including outside leaves and intermediate leaves formed with registering openings adjacent their inner edges; a reinforcing strip connected to one of said outside sheets adjacent its inner edge and connected to the inside inner edge of the adjacent cover, said strip having a hinged portion between its connections to said outside leaf and said cover, and said strip being formed with spaced openings on opposite sides of said hinged portion respectively and aligned with the 70 openings in said leaves; and attaching means passing through the openings in said leaves and in said reinforcing strip and being secured to said back.

75 2. In a book, the combination with an outer structure comprising a back; covers operatively

connected to said back; of a stack of leaves including outside leaves and intermediate leaves formed with registering openings adjacent their inner edges; reinforcing strips respectively connected to said outside sheets adjacent their inner edges and connected to the inside inner edge portions of the respectively adjacent covers, each of said strips having a hinged portion between its connections to the associated leaf and cover and each said strip being formed with 10 spaced openings on opposite sides of said hinged portion respectively and aligned with the openings in said leaves; a flexible attaching band; means securing said band to said outer structure, said flexible attaching band passing through the 15 openings in said leaves and the openings in said reinforcing strips and thereby anchoring said leaves to said outer structure.

3. In a book, the combination of a back; covers operatively connected to said back; a stack of 20 leaves including outside leaves and intermediate leaves formed with registering openings adjacent their inner edges; reinforcing strips respectively connected to said outside sheets adjacent their inner edges and connected to the 25 inside inner edge portions of the respectively adjacent covers, each of said strips having a hinged portion between its connections to the associated leaf and cover and each said strip being formed with spaced openings on opposite sides of said hinged portion respectively and aligned with the openings in said leaves; a flexible attaching band passing through the 30 openings in said leaves and the openings in said reinforcing strips and thereby anchoring said 35 leaves to said covers; and means anchoring said band to said back independently of said covers.

4. In a book, the combination of a back; covers operatively connected to said back; a stack of 40 leaves including outside leaves and intermediate leaves formed with registering openings adjacent their inner edges; a reinforcing strip of flexible material connected to one of said outside sheets adjacent its inner edge and connected to the inside inner edge of the adjacent 45 cover, said strip being folded to provide a hinged portion between its connections to said outside leaf and said cover, and said strip being formed with spaced openings on opposite sides of said hinged portion respectively and aligned with the 50 openings in said leaves; and attaching means passing through the openings in said leaves and in said reinforcing strip and being secured to said back.

5. In a book, the combination of a back; covers operatively connected to said back; a stack of leaves including outside leaves and intermediate leaves formed with registering openings adjacent their inner edges; a reinforcing strip glued to one of said outside sheets adjacent its inner edge and glued to the inside inner edge of the adjacent cover, said strip having a hinged portion between its connections to said outside leaf and said cover, and said strip being formed with spaced openings on opposite sides of said 65 hinged portion respectively and aligned with the openings in said leaves; and attaching means passing through the openings in said leaves and in said reinforcing strip and being secured to said back.

70 6. In a book, the combination of a back; covers operatively connected to said back; a stack of leaves including outside leaves and intermediate leaves formed with registering openings adjacent their inner edges; a reinforcing strip 75

connected to one of said outside sheets adjacent its inner edge and connected to the inside inner edge of the adjacent cover, said strip having a hinged portion between its connections to said 5 outside leaf and said cover, and said strip being formed with spaced openings on opposite sides of said hinged portion respectively and aligned with the openings in said leaves; and a flexible attaching band passing through the openings 10 in said leaves and in said reinforcing strip and being embedded in said back.

7. In a book, the combination of a back proper, a stack of leaves; a back-binding member comprising a strip of sheet material twice folded lengthwise and shaped to form a flattened tube with a projecting wing appended thereto, one outer face of said member being secured to the back proper and the other outer face thereof abutting the inner edges of said leaves, mutually adjacent inner faces of said member being free from 15 jointure to each other whereby to permit relative movement therebetween; and means for binding said leaves to said back proper, said means being partly embedded between the first 20 said outer face of the tube and said projecting wing.

8. In a book, the combination of a back proper, a stack of leaves provided with mutually registering openings adjacent the edges to be bound; 30 a back-binding member comprising a strip of sheet material twice folded lengthwise and shaped to form a flattened tube, one outer face of said member being secured to the back proper and the other outer face thereof abutting the

inner edges of said leaves, mutually adjacent inner faces of said member being free from jointure to each other whereby to permit relative movement therebetween; and means for binding said leaves to said back proper, said 5 means comprising a band of flexible material passing through the registering openings in said leaves and being anchored to said back proper.

9. In a book, the combination of a back proper, a stack of leaves provided with mutually registering openings adjacent the edges to be bound; 10 a back-binding member comprising a strip of sheet material twice folded lengthwise and shaped to form a flattened tube, one outer face of said member being secured to the back proper 15 and the other outer face thereof abutting the inner edges of said leaves, mutually adjacent inner faces of said member being free from jointure to each other whereby to permit relative movement therebetween; means for binding 20 said leaves to said back proper, said means comprising a band of flexible material passing through the registering openings in said leaves, means anchoring said band to said back-binding member, and a reinforcing strip glued to the 25 inner edge portion of one outside leaf of said stack and being glued to the adjacent inner inside edge portion of the adjacent cover, said reinforcing strip being formed with two spaced aligned openings, one of which registers with the 30 openings in said leaves, said band passing through both the openings in said reinforcing strip.

HARVEY B. MARTLING.
